ATTORNEY

UNITED STATES PATENT OFFICE

MARTIN M. MARTINI, OF NEW FAIRFIELD, CONNECTICUT

GUARD FOR GUTTERS

Application filed July 14, 1928. Serial No. 292,810.

This invention relates to an improvement in roof gutters or eaves troughs, and relates more particularly to means for preventing leaves and rubbish from entering and clogging gutters or troughs and their drain pipes, and so preventing the same from overflowing or dripping water during rainy weather, and also to make it unnecessary to clean the gutters or troughs.

More specifically, the invention contemplates a guard screen for roof gutters or eaves troughs to prevent clogging and allowing rain water to run off through drain pipes connected therewith, the screen being made up from sections of improved construction, whereby they may be fitted to gutters or troughs varying in width, and also to lead drip water from thawing ice or sleet, into the gutters or troughs.

The nature of the invention and its distinguishing features and advantages will appear when the following specification is read in connection with the accompanying drawing, in which

Figure 1, is a transverse sectional view taken on the line 1—1, of Fig. 2.

Fig. 2, is a plan view of a portion of eaves troughs which join each other in corner formation.

Fig. 3, is a detail sectional view, the section being taken on the line 3—3, of Fig. 2.

Fig. 4, is a plan view of one of the screen sections and attaching means therefor.

In the drawing there has been illustrated one embodiment of the invention applied to sheet metal eaves troughs or gutters 10, which join each other in angular or corner construction to be suspended in the usual manner contiguous the corner of the bases of eaves of a roof, to receive rain water and water from ice and sleet, which is carried off by the usual drain pipes. These troughs or gutters are strengthened in the usual manner by a rolled flange 11 on the upper outer edges.

The means by which the objects of the invention are attained in conjunction with the troughs or gutter 10, consists of a guard screen designed and adapted to be secured in position in the mouths of the troughs or gutters.

This screen is made from sections of two

types 12 and 13, having the same improved features of construction, although they differ only in shape. The sections 13 serve in the juncture or corner of intercommunicating troughs or gutters. Each of the sections 12 and 13 is made of foraminous material or woven wire of suitable mesh. The opposite sides of each section are provided respectively with upwardly and exteriorly opening longitudinal marginal depressions or channels 14, which are produced by bending the material downwardly, outwardly and then upwardly. A suitable sheet metal binding 15 is secured to the outer upturned edge of each channel 14. The binding 15 makes a close fit with the adjacent upturned edge of the trough. One end of each section 12 and 13 is cut at a right angle with respect to the sides, and a suitable sheet metal binding 16 is secured to the same to present a straight edge. The opposite end of the section is cut and bent to provide an offset rest 17, and a suitable sheet metal binding 18 is secured to the rest 17. Each rest 17 serves to support the abutting or meeting edge of the contiguous section, producing an overlapped joint, as shown most clearly in Fig. 3.

In order to securely hold the sections 12 and 13 in place in the mouths of the troughs or gutters 10, there is provided means in the form of fastening members or wires 19. Each member 19 is bent to provide a central up-standing loop 20 and down-turned ends 21. A suitable number of members 19 is used in conjunction with each of the sections 12 and 13. Each member 19 has its loop 20 disposed between two of the wires of the screen section, and the ends 21 are sprung over and in engagement respectively with the opposite upturned sides of the trough, as shown most clearly in Fig. 1. In this manner the screen sections are held in place. The sections 12 may be made in two or three foot lengths, two fastening members 19 being sufficient to hold the two foot sections, whereas three members 19 being sufficient to hold or support the three foot sections. Two members 19 are sufficient to support each corner section 13.

From the foregoing it will be apparent that the general construction of the guard well adapts it, for the purpose of preventing

accumulation of leaves and rubbish in the troughs or gutters, thereby preventing clogging and consequent overflowing of rain water due to stuffed drain pipes; that by providing the channels 14, the sections may be made to fit troughs or gutters which vary in width; and that the channels 14 serve to lead drip water from thawing ice or sleet, into the troughs or gutters.

10 I claim:

1. A guard for an eaves trough or gutter, consisting of a screen having longitudinal marginal side channels which will intervene the body of the screen and the side portions of the trough or gutter, when the screen is secured in the mouth thereof.
- 15 2. A guard for an eaves trough or gutter, consisting of a screen having upwardly and exteriorly opening longitudinal marginal side channels, one end of the screen terminating in a straight transverse edge, and the opposite end terminating in an offset edge portion which serves as a rest.
- 20 3. A guard for the corner of intercommunicating eaves troughs or gutters, consisting of a screen substantially of L-shape, and having its lateral edge portions bent downwardly, outwardly and upwardly to form continuous longitudinal channels.
- 25 4. The combination with an eaves trough or gutter, of a guard screen secured in place in the mouth of the trough or gutter, said screen having upwardly and exteriorly opening longitudinal marginal channels respectively abutting the opposite upturned edges of the trough or gutter.
- 30 5. The combination with an eaves trough or gutter, of a guard consisting of screen sections, each section provided with upwardly and exteriorly opening longitudinal marginal channels, and an offset edge portion constituting a rest for the abutting edge of a contiguous section, the channels of the sections being in abutting engagement respectively with the opposite upturned edges of the trough or gutter, and means for securing said sections in place in the mouth of the trough or gutter.

MARTIN M. MARTINI.
